[57] **CLAIM**

The ornamental design for a hydraulic tractor hoist, as shown and described.

DESCRIPTION

FIG. 1 is a front elevational view of the hydraulic tractor hoist showing my new design;

FIG. 2 is a rear elevational view thereof;

FIG. 3 is an enlarged left side elevational view thereof;

FIG. 4 is an enlarged right side elevational view thereof;

FIG. 5 is a top plan view thereof;

FIG. 6 is a bottom plan view thereof; and,

FIG. 7 is a perspective view thereof.

The cables disclosed in FIGS. 1-5 and 7 are shown broken away to indicate indeterminate length.
